ROTARY HOOK FOR SEWING MACHINES

George Sauer, Berwyn, Ill., assignor to Union Special Machine Company, Chicago, Ill., a corporation of Illinois

Application November 30, 1934, Serial No. 755,495

8 Claims. (Cl. 112—256)

The present invention relates to new and useful improvements in a rotary hook for a lock-stitch sewing machine and more particularly to improved means for furnishing lubricant to the interengaging parts between the rotary hook and the stationary bobbin casing.

An object of the invention is to provide, in a sewing machine, means for furnishing lubricant to the interengaging parts between the rotary hook and the stationary bobbin casing wherein means are provided for delivering lubricant from the end of the bushing for the rotary hook actuating shaft to an inclined surface on the hub of the rotary hook and wherein the lubricant is thus caused to flow by centrifugal force to the interengaging parts.

A further object of the invention is to provide, in a sewing machine, means for furnishing lubricant to the interengaging parts between the rotary hook and the stationary bobbin casing wherein the end of the bushing for the hook actuating shaft and the hub of the rotary hook are fitted in overlapping relationship in a manner to permit lubricant to be delivered by gravity from the bushing to the hub of the hook and wherein means are provided for causing the lubricant to flow from the hub of the hook to the interengaging parts by centrifugal force.

The above and other objects of the invention will in part be obvious and will be hereinafter more fully pointed out.

In the accompanying drawings:

Figure 1 is a side elevation, in section, showing the assembled rotary hook, the actuating shaft therefor and the bushing within which the shaft rotates.

Figure 2 is a sectional view along line 2—2 of Fig. 1.

Figure 3 is a side elevation, in section, similar to Fig. 1 but showing another form of the invention.

Figure 4 is a sectional view along line 4—4 of Fig. 3.

Figure 5 is a sectional view along line 5—5 of Fig. 3.

The invention relates generally to the provision of lubricating means for furnishing lubricant to the interengaging parts between the rotary hook and the stationary bobbin casing. The rotary hook is fixed to the end of a rotating shaft and the bobbin casing is mounted within and supported by the rotary hook. The bobbin casing is provided with a circumferential rib which engages a groove or raceway in the rotary hook and thus prevents lateral movement

of the bobbin casing relative to the rotary hook. A portion of the bobbin casing engages a fixed part of the sewing machine in order to prevent rotation of the casing within the rotary hook. The actuating shaft for the rotary hook is supported in a bushing which is mounted in a bearing bracket depending from the work support of the sewing machine. The shaft bushing is provided with a groove through which lubricant may flow from a source of supply to the 10 end thereof. The hub of the rotary hook and the end of the bushing are constructed in such a manner that they fit together in overlapping relationship. The hub is provided with an inclined portion to which lubricant flows by gravity from the groove in the bushing. The inclined portion on the hub of the rotary hook passes through the rear face of the hook so that lubricant may flow to the inclined inner face of the hook rim along which it is caused to flow 20 to the interengaging parts by centrifugal force.

Referring more in detail to the accompanying drawings and particularly, at this time, to Figs. 1 and 2, the invention is shown as applied to a sewing machine having a work support 10 which is provided with a depending bearing bracket 11 in which is mounted a bushing 12. The actuating shaft 13 is mounted within the bushing 12 and the rotary hook 14 is secured to the end of the shaft by a screw 15 or the like. The particular manner in which the actuating shaft for the rotary hook is driven forms no part of the present invention and it is to be clearly understood that it may be driven in any suitable manner. For purposes of illustration, however, the shaft 13 may be driven by suitable intermeshing gears, as shown in the copending application of George Sauer, Serial No. 688,512, filed September 7, 1933, and described in detail in the copending application of Norman V. Christensen et al., Serial No. 40 670,186, filed May 9, 1933. The shaft may also be driven in the manner shown and described in the copending applications of George Sauer, Serial Nos. 716,415 and 716,416, filed March 19, 1934.

The rotary hook 14 is of usual cup-shaped construction having a rim portion 16 and a hub 17 joined to the rim by a rear face portion 18. The hub is conical in longitudinal section, the larger end being adjacent the rear face of the hook. One side wall of the cup is cut away to provide a hook which is adapted to enter the needle thread loop and carry the same about the bobbin casing 19 which is also cup-shaped and is adapted to receive a bobbin 20 therein. The bobbin is 55

held within the bobbin casing 19 by a cover or carrier 21. The bobbin casing 19 is provided with a circumferential rib 22 which fits within a groove or raceway 23 in the rim portion 16 of the rotary hook. The rib 22 and raceway 23 form interengaging parts between the rotary hook and the bobbin casing to prevent lateral movement of the casing relative to the hook. The bobbin casing is provided with a projecting portion 24 which 5 engages a fixed part of the sewing machine in order to prevent the rotation thereof within the hook. The rotary hook operates in the usual manner and further description thereof is not considered necessary.

15 The depending bearing bracket 11 is provided with an oil hole 25 which communicates with an opening 26 in the bushing 12. The opening 26 in the bushing communicates with a recess 27 formed around a portion of the inner periphery 20 of the bushing. An axial groove 28 in the bushing leads from the recess therein to a vertical groove 29 formed in the end thereof. The free end of the bushing is offset to provide a reduced portion 30 which fits within a recess 31 formed in 25 the end of the hub 17. The recess 31 is bounded by a wall portion 32 which is inclined toward the reduced end 30 of the bushing in order to prevent the escape of lubricant therefrom. The hub 17 is provided with an inclined port 33 which 30 extends from the recess 31 to the inner face of the rotary hook. Oil admitted to the oil hole 25 in the bracket 11 will flow through the opening 26 to the recess 27 in the bushing and from there it will follow the axial groove 28 and descend by 35 gravity through the groove 29 to the recess 30 in the hub. As the hook rotates, the oil will be caused to flow through the port 33 to the inner face of the hook by centrifugal force which will cause it to follow the inclined inner face 34 of the 40 rim portion 16 to the interengaging parts between the hook and the bobbin casing, that is, to the interfitting rib 22 and raceway 23 in order to lubricate the same.

In Figs. 3, 4, and 5 of the accompanying drawings, a slightly modified form of the invention is shown. The bobbin 20, bobbin casing 19 and the rotary hook are assembled in the same manner described in connection with Fig. 1 and further description thereof is not considered necessary at 45 this time. Oil admitted to the oil hole 25 in the depending bearing bracket 11 will flow through the opening 26 in the bushing 12a to the recess 27 therein. Oil will pass from the recess 27 through the groove 28a in the bushing and then 50 through the vertical groove 29a at the end thereof. The free end of the bushing 12a is offset to provide an enlarged recessed or flanged portion 30a which fits over the smaller end of the tapered hub 17a of the rotary hook. The rear 55 face 18a of the rotary hook is provided with a groove 37 at the inner edge of the hub 17a. Inclined ports 36 extend through the face of the rotary hook from the groove 37 to the inner face thereof. Oil descending the groove 29a in the 60 end of the bushing 12a will be picked up by the inclined surface 35 of the hub and will be caused to flow into the groove 37 from which it will find its way through ports 36 to the inclined inner face 34 of the rim 16 and will be caused to 65 reach the interengaging parts between the bobbin casing and the rotary hook by centrifugal force occasioned by the rotation of the hook.

From the foregoing description, it will be seen that highly efficient means for furnishing lubricant to the inter-engaging parts between the

rotary hook and the stationary bobbin casing is herewith provided and it is to be clearly understood that minor changes in the details of construction and arrangement of parts may be made without departing from the scope of the invention 5 as set forth in the appended claims.

Having thus described the invention, what I claim as new and desire to secure by Letters Patent is:

1. In a sewing machine, the combination of a 10 rotary hook having a hub and a rim portion, a stationary bobbin casing supported within said hook, a shaft on which said hub is mounted, said casing and rim portion having interengaging parts to prevent relative lateral movement between 15 said casing and said hook, said hub having an oil conducting path substantially co-extensive therewith and inclined lengthwise thereof, means disposed exteriorly of said shaft for delivering oil thereto, and means including said oil conducting 20 path for furnishing lubricant to said interengaging parts by centrifugal force.

2. In a sewing machine, the combination of a rotary hook having a hub, a stationary bobbin casing supported within said hook, said casing 25 and hook having interengaging parts to prevent relative lateral movement therebetween, an actuating shaft on which said hub is secured, a bushing within which said shaft rotates, means for supplying lubricant from the end of said bushing 30 to said hub, and means including a lubricant path on said hub for furnishing lubricant to said interengaging parts, said lubricant path extending from a point adjacent the end of said bushing 35 throughout the length thereof.

3. In a sewing machine, the combination of a rotary hook having a hub and a rim portion, said rim portion having an inclined inner face, a stationary bobbin casing supported within said hook, 40 said casing and rim portion having interengaging parts to prevent relative lateral movement between said casing and said hook, an actuating shaft on which said hub is secured, a bushing within which said shaft rotates, said bushing 45 having an axial groove leading to the end thereof, means for furnishing lubricant to said groove, said hub and the end of said bushing having overlapping portions whereby lubricant may pass from the end of said bushing to said hub, and means for directing lubricant from said hub to the inner face of said rim portion whereby lubricant is caused to flow by centrifugal force to said 50 interengaging parts.

4. In a sewing machine, the combination of a 55 rotary hook having a hub and rim portion connected by a face portion, a stationary bobbin casing supported within said hook, a shaft on which said hub is mounted, said casing and rim portion having interengaging parts to prevent relative lateral movement between said casing and said hook, said hub having a port disposed entirely within the hub and inclined lengthwise thereof and extending to the inner surface of said face portion, and means disposed exteriorly of said 60 shaft for delivering lubricant to said port whereby lubricant is caused to flow to the inner face of said rim portion and to said interengaging parts by centrifugal force.

5. In a sewing machine, the combination of a 70 rotary hook having a hub, a stationary bobbin casing supported within said hook, said casing and hook having interengaging parts to prevent relative lateral movement therebetween, an actuating shaft on which said hub is secured, a bush-

ing within which said shaft rotates, said bushing having an oil conduit leading to the end thereof, said hub having a flange portion overlapping the end of said bushing and forming an annular recess whereby oil may flow thereto from the end of said bushing, and means for directing lubricant from said recess to said interengaging parts.

5 6. In a sewing machine, the combination of a rotary hook having a hub, a stationary bobbin 10 casing supported within said hook, said casing and hook having interengaging parts to prevent relative lateral movement therebetween, an actuating shaft on which said hub is secured, a bushing within which said shaft rotates, said bushing 15 having an oil conduit leading to the end thereof, the end of said bushing being provided with an annular flange overlapping the end of said hub whereby to permit lubricant to flow to said hub, and means for directing lubricant from said hub 20 to said interengaging parts.

7. In a sewing machine, the combination of a rotary hook having a hub, a rim portion and a connecting face portion, said face portion having an annular groove on the rear surface thereof 25 and inclined ports leading from said groove to the inner surface of said face portion, of a stationary bobbin casing supported within said hook,

said casing and rim portion having interengaging parts to prevent relative lateral movement between said casing and said hook, and means for furnishing lubricant to said groove whereby the lubricant will be caused to flow by centrifugal 5 force through said ports to said interengaging parts.

8. In a sewing machine, the combination of a rotary hook having a hub, a rim portion and a connecting face portion, said face portion having an annular groove on the rear surface thereof and inclined ports leading therefrom to the inner surface thereof, of a stationary bobbin casing supported within said hook, said casing and rim portion having interengaging parts to prevent relative lateral movement between said casing and said hook, said hub having an inclined outer surface merging into said groove, an actuating shaft on which said hub is secured, a bushing in which said shaft rotates, said bushing having a flanged 20 end overlapping the smaller end of said hub, means for furnishing lubricant from the end of said bushing to the inclined surface of said hub whereby lubricant will be caused to flow by centrifugal force to said interengaging parts. 25

GEORGE SAUER.
